ATTORNEY

UNITED STATES PATENT OFFICE.

JOHN M. CLARK, OF WHITESTONE, NEW YORK.

STEAM-ENGINE.

1,152,488.

Specification of Letters Patent. Patented Sept. 7, 1915.

Application filed January 6, 1915. Serial No. 726.

To all whom it may concern:

Be it known that I, JOHN M. CLARK, a citizen of the United States, and residing at Whitestone, Queens county, New York, have 5 invented certain new and useful Improvements in Steam-Engines, of which the following is a specification.

This invention relates to steam engines and has particular reference to improvements 10 on a steam engine patented by me March 22, 1904, No. 755,453.

In my present invention I provide novel 15 improved valve mechanism by which I can deliver the motive fluid to the valve chamber close up to the cylinder, so that a minimum loss through condensation only occurs, and I also provide improved means for controlling the action of the valves by which an early, quick cut-off is obtained, allowing of 20 greater expansion of the steam behind the piston resulting in a higher power development.

My present invention also provides a 25 structure of the class described which possesses practically perfect balance for the reason that the cylinder and the parts moving with it are accurately counterbalanced by the piston and the parts moving with it, and for this reason there is practically no 30 vibration and great speed can be developed and high horse power delivered at the crank shaft.

A further object of my improved steam 35 engine is to provide means, carried on a crank pin of the shaft, for imparting to the valves a quick sharp cut-off movement thereby obtaining longer expansive action on the piston, as for instance if the cut-off is at one third of the stroke, the expansion 40 continues for the balance of the stroke, thus providing a double acting engine nearly if not quite equal to a compound engine of the same bore and crank stroke.

My invention provides an engine in which 45 the piston and cylinder move in opposite directions the same distance simultaneously; thus if the crank stroke is six inches the piston head passes through twelve inches of cylinder, by which construction the high 50 speed of the short stroke engine combined with the power and economy of the slow long stroke engine is obtained.

The invention further provides new and novel arrangements and construction of

parts to be hereinafter described and 55 claimed.

In the drawings forming part of this specification similar reference characters are employed to designate corresponding parts and in which,

Figure 1, is a sectional elevation of my 60 improved engine, some of the supporting frame being omitted. Fig. 2, is a view at a right angle to Fig. 1, looking in the direction of the arrow A, the supporting frame 65 being entirely removed.

In the drawings I have shown at *a*, the cylinder of the engine, and at *b*, the piston provided with the usual rod *c*, connected to a cross head *d*, movable in guides *e*, to 70 which cross head *d*, is pivoted a pitman *f* connected to a crank *g*, of the engine shaft *h*. The cylinder *a*, is closed at the ends by the usual heads *i*, and *j*, which have tubular integral elbow extensions *k*, and *l*, forming 75 ports *m* and *n*, through which the motive fluid passes during the operation of the engine. The cylinder heads *i* and *j*, are secured in place by bolts *o*, extending the length of the cylinders and through the 80 heads to receive nuts as clearly shown, and the cylinder heads are provided with integral guide half blocks *p*, to which are bolted cap blocks *q*, which form guides through which a fixed standard *r*, passes to 85 support and guide the cylinder in its reciprocating operative movement.

The bottom cylinder head *j*, is provided with the usual stuffing-box *s*, and two pairs of spaced perforated lugs *t*, between which are pivotally carried a pair of connecting rods or links *u*, having pivotal connection at their lower ends to cranks *v*, and *w*, of the engine shaft *h*, as shown.

Tubular castings *X* and *Y* bolted to the 95 extensions *k*, and *l*, are provided with central bores and with lateral ports *x'* and *y'* which register with the ports *m*, and *n*, and these castings are also provided with flanged elbows *x²* and *y²* to which are bolted flanged 100 exhaust pipe sections *z*, projecting into an exhaust cylinder *z'* of greater diameter than the pipe sections. The free ends of the said pipe sections are spaced apart to form a free exhaust space *z²* to allow of free exit 105 of the used motive fluid into the cylinder *z'* and out through the port *z³* as will be readily understood. Threaded into the in-

ner ends of the tubular castings, X and Y, is a tube 5, provided with circumferentially arranged ports 6, entering into a steam chamber 7 formed by a cylinder 8, of greater diameter than the tube 5, as clearly shown in Fig. 1, of the drawings and said cylinder 8, is provided with an inlet port 9, through which the steam is delivered from the boiler.

I provide effective means for controlling

- 10 steam under high pressure and delivering it close up to the ends of the cylinder, consisting of companion valves 10 secured to a rod 14, passing through the casting X, tube 5, casting Y, and out through a stuffing box 12 thereon, and it will be understood the casting X, tube 5 and casting Y, collectively form a valve chamber 14, in which the steam is confined between the balanced companion valves 10, so that in the operation of the engine, thrust is greatly reduced. The cylinders z' and 8, are secured one to the other and both are secured against movement by a bracket 15, rising from the frame 16, of the engine. The lower free end of the valve rod 14, is pivotally connected to a link 17 which is in turn pivoted to a lever 18, having pivotal connection with one of the connecting rods or links u, and pivoted to this lever 18, is a rod 19, connected at its other end to an eccentric strap 20, carried on an eccentric disk 21, mounted on and secured to the crank pin 22, of the crank 2, of the engine shaft as shown in Fig. 2, of the drawings.

35 The operation of my improved engine will be readily understood by those skilled in the art to which it appertains and a detailed description thereof is not deemed necessary, the improvement being particularly constituted by the construction of the valves and valve chamber and the means for giving the valves quick cut-off action.

40 Changes in the construction and arrangement of parts may be made within the scope of the appended claims without departing from the spirit of the invention or sacrificing its advantages.

45 What I claim is:—

- 50 1. In an engine of the class described a cylinder and a piston therein, said cylinder having heads formed with extensions provided with ports, castings bolted to said extensions and having ports registering with the ports in the extensions, said castings being provided with longitudinal bores, a tube having ports and being connected to the castings, the bore thereof registering with that of the castings to form a valve chamber, a fixed steam cylinder of greater diameter than the tube and through which the tube is adapted to slide, companion valves slideable in the valve chamber, means for giving the cylinder and piston opposite movements and for operating the valves.
- 55 2. In an engine having a reciprocating

cylinder and a piston therein, a valve chamber arranged alongside the cylinder and extending above and below the same and being provided with lateral ports, companion valves operating in said chamber to open 70 and close the ports, a rod connecting the valves and extending downwardly through the end of the valve chamber and geared in connection with an eccentric on a crank pin of the engine shaft and means for giving 75 the cylinder and piston opposite movements.

3. In a steam engine a cylinder having heads provided with tubular elbow extensions, a valve chamber carried by the extensions, valves in said chamber to control ports 80 opening into the chamber above and below the ends of the cylinder, a fixed steam inlet cylinder surrounding the valve chamber and in communication therewith and through which the valve chamber moves, means for 85 operating the valves and for giving the cylinder and piston opposite movements for the purpose described.

4. In a steam engine, a cylinder and a piston therein, said cylinder being provided 90 with tubular elbow extensions, a valve casing carried thereby and having ports registering with ports in the extensions, an inlet steam cylinder of greater diameter than the valve chamber and surrounding the same to 95 provide a steam chamber in communication with the valve casing, elbow extensions at the top and bottom of the valve casing, exhaust pipe sections secured thereto, a fixed exhaust cylinder of greater diameter than 100 the exhaust pipe sections and inclosing the free ends thereof to form an exhaust steam chamber through which the pipe sections move, valves in said casing to open and close the ports, means for operating the valves 105 and for operating the cylinder and piston in opposite directions.

5. In an engine of the class described a cylinder and a piston therein, a valve casing at the side of the cylinder having ports communicating with the top and bottom thereof, an inlet steam cylinder surrounding the casing and communicating therewith, exhaust pipe sections carried by the valve casing, an exhaust steam cylinder of greater diameter 110 than the exhaust pipe sections and inclosing the spaced free ends thereof to form an exhaust steam chamber, the said inlet and exhaust cylinders being connected one to the other and to the frame of the engine, a pair 115 of valves in said casing, means for operating the valves and for giving the piston and cylinder of the engine opposite movements.

6. In a steam engine the combination with a reciprocating cylinder adapted to move in 125 a direction opposite its piston, a valve casing carried by the cylinder, fixed steam inlet and outlet cylinders communicating therewith, and through the former of which the casing is adapted to move, companion valves 130

in said casing, means for giving the cylinder
and piston opposite movements and means
carried by a crank pin of the engine shaft
for giving the valves simultaneous recipro-
5 cating movement.

In testimony whereof, I have signed my
name to this specification in the presence of

two subscribing witnesses, this 5th day of
January, 1915.

JOHN M. CLARK.
